UNITED STATES PATENT OFFICE.

WILLIAM ANDREW ROBERT ANGUS, OF WINNIPEG, MANITOBA, CANADA.

RAIL-ANCHOR.

1,401,856.

Specification of Letters Patent. Patented Dec. 27, 1921.

Application filed March 14, 1921. Serial No. 452,152.

To all whom it may concern:

Be it known that I, WILLIAM ANDREW ROBERT ANGUS, a subject of Great Britain, and resident of the city of Winnipeg, in the 5 Province of Manitoba, Canada, have invented certain new and useful Improvements in Rail-Anchors, of which the following is the specification.

The invention relates to improvements in 10 rail anchors and an object of the invention is to provide an anchor which will prevent a track rail from creeping on the ties or the tie from moving in respect to the rail.

A further object is to construct the anchor 15 in a simple, durable and inexpensive manner and so that it can be readily put on and clamped in place.

A further object is to provide the anchor 20 with a clamping member that will tighten in the creeping of the rail in say the positive direction, and will allow of movement of the rail in the negative direction under all conditions, and is further arranged so that it bites the rail at all times and a negative 25 rail movement having occurred it relocks in the subsequent positive rail movement.

With the above more important objects in view the invention consists essentially in the arrangement and construction of parts 30 hereinafter more particularly described and later pointed out in the appended claims, reference being had to the accompanying drawing in which:—

Figure 1 is a front view of the appliance 35 as it appears attached to the rail base, the rail being shown in vertical section.

Fig. 2 is a plan view of the parts appearing in Fig. 1.

Fig. 3 is a horizontal sectional view at 40 3—3' Fig. 1 and looking downwardly.

Fig. 4 is a vertical sectional view at 4—4' and looking to the left, the rail base being removed.

In the drawing like characters of reference 45 indicate corresponding parts in the several figures.

1 is a track rail of ordinary construction presenting the head 2, web 3 and base 4. The rail is mounted on ties 5 in the usual 50 manner, being fastened to the ties by spikes 6.

In actual practice it is found that the constant movement of traffic produces a loosening of the spikes, a creeping of the rails on the ties and very often a movement of the tie in respect to the rail.

As a general rule the rail in creeping moves in the direction of the movement of traffic. In some cases however, such as in single tracking with traffic in both directions, the rail will creep in the direction of the heaviest traffic. My device, shortly described, is placed on the rails with due regard to the condition met with, its object being to prevent creeping in the direction 60 which it occurs. The anchors used are constructed in detail as now described.

7 is a shank having one end fitted with a hook like stationary clamping jaw 8 and the other end presenting a horizontally disposed bearing face 9 with which I associate a vertically disposed neck 10 parallel to the rail base, a horizontally disposed inturned flange 11 extending from the neck and overhanging the bearing face 9 and a vertical 70 wall or web 12. This wall connects the flange, neck and base at what might be considered the rear side of the anchor and it is projected below the shank and is extended rearwardly to provide a vertically disposed bearing face 13 for engagement with the tie. By observing Fig. 2 it will be seen that this bearing face is contained in a vertical plane somewhat to the rear of the vertical plane containing the rear side of the 75 shank so that when the anchor is in place there is a clearance space 14 reserved between the shank, clamping jaw 8 and the tie.

The neck 10 and web 13 are continuous 80 and are curved at their juncture point to provide a semi-circular bearing face or shoulder 15 which forms the swiveling or turning point for a movable clamping member 16 shortly described in detail.

The shank 7 is somewhat longer than the width of the rail base on which it is used and it is here to be noticed that the left end of the shank is in a lower horizontal plane than the jaw end, this being accomplished 95 by bending downwardly as indicated at 7' the body of the shank. This downward bend brings the underside of the flange 11 into the same horizontal plane which contains the underside of the base rail and provides also a wedge shaped clearance space indicated at 7" between the base of the rail and the bent part of the shank.

The clamping member 16 presents spaced upper and lower jaws 17 and 18 and an extending pivot arm 19, the jaws having their opposing faces shaped more or less comple-

mentary to the exposed faces of the rail base which they grip, one on top and the other beneath. The arm 19 is adapted to pass between the flange 11 and face 9 and terminates in a semi-circular rounded end adapted to the seat against the curved face 15.

When the removable clamping member is in place the under jaw extends into the clearance space 7^x and the general arrangement 10 of the said member is such that when in working position it is disposed angularly to the rail as best shown in Fig. 2.

The shank 7 is supplied with a forwardly extending horizontally disposed lug 20 and 15 the lug is provided with a suitable opening to receive a retaining pin 21. The inserted pin is positioned preferably close to the rail base and somewhat in the rear of the rear side of the clamping member 16.

20 When this anchor is to be used it is attached to the base of the rail and adjoining a tie, due consideration being given to the direction in which the particular rail creeps. The direction of creeping of the rail in the 25 present instance is indicated by the applied arrow in Fig. 2. The shank having been placed as shown with the stationary jaw 8 gripping one edge of the rail but clear of the face of the tie and the face 13 against the 30 face of the tie at the other side of the rail the sectionman or such like person then inserts the clamping member 16 in the position shown with the jaws gripping the rail base and the arm seated in the curved pocket 35 15. Although it is not essentially necessary to drive the clamping member in place it is as well to tap it with a hammer to insure of the initial comparatively tight gripping of the jaws 17 and 18 on the base of the rail. 40 After the member 16 has been put in place the pin 21 is inserted, this pin not being used to maintain the clamping member tightly clamped in place but to limit the movement of the clamping member in the negative creeping movement of the rail. The 45 action of the anchor is as follows.

Upon the rail creeping in the direction of the applied arrow it carries the clamping jaw 8 with it as well as the jaws 17 and 18 50 which hang to the rail. The left hand end of the anchor cannot move by reason of the fact that the face 13 is engaged with the tie which is considered as stationary. I might also here explain that the clearance space 55 14 permits the jaw 8 to move toward the tie. The movement of the parts above explained is comparatively small and momentary, for the instant this movement occurs the clamping member 16 swings in the direction 60 of the movement of the rail and consequently causes the jaws 17 and 18 to move inwardly and grip the base of the rail more severely. The device is particularly quick acting as the double movement provided 65 intensifies the quick gripping feature. Ac-

cordingly any detrimental creeping movement of the rails is stopped.

When, under normal conditions, there is a negative or reverse creeping action of the rail, the whole anchor moves back with the 70 rail, the clamping member remaining inert and tightly gripped. With abnormal conditions however, such as where frozen ground is met with and it is impossible for the shank to move in the negative direction, the clamping 75 member can either swing back, or move bodily back with the rail, but in either case it maintains a grip on the rail base. If it goes bodily back with the rail, it engages the pin, such preventing it from getting out of 80 proper alignment for return movement with the other working parts. The point which I wish to particularly emphasize is that the jaws of the clamping member never cease to grip the rail base sufficiently tight so that 85 it will not move back with the rail and re-lock it in all positive creeping movements.

What I claim as my invention is:—

1. In a rail anchor, the combination with the base of a rail and a tie supporting the 90 rail, of a member adapted to extend under the rail at the side of the tie and having one end spaced from the tie and provided with means for engaging the rail base and the other end engaging the tie and provided with a bearing face extending beyond the rail base, a clamping member disposed on the said bearing face and at an angular position to the rail and having the outer end swivelly mounted and the inner 95 end engaging the adjacent side of the rail base.

2. In a rail anchor, the combination with the base of a rail and a tie supporting the 105 rail, of a member adapted to extend under the rail at the side of the tie and having one end spaced from the tie and provided with means for engaging the rail base and the other end engaging the tie and provided with a bearing face extending beyond the rail base, a clamping member disposed on said bearing face and angularly positioned in respect to the rail and having the outer end anchored for rocking movement while permitting a turning movement of 110 the clamping member and the inner end provided with jaws receiving the adjacent edge of the rail base.

3. In a rail anchor, the combination with the base of a rail and a tie supporting the 120 rail, of a member adapted to extend under the rail and having one end spaced from the tie and provided with means for engaging said rail base and the other end engaging the tie and provided with a horizontally 125 disposed bearing face extending beyond the rail and a swinging clamping member having one end anchored to the bearing face and the other end gripping the rail base, the said clamping member being disposed 130

- at an angle to the rail whereby in the movement of the rail in one direction the said clamping member swings with the rail and by virtue of its angular position grips the rail more positively.
5. In a rail anchor, the combination with the base of a rail and a tie supporting the rail, of a member adapted to extend under the rail and having one end spaced from the tie and provided with means for engaging said rail base and the other end engaging the tie and provided with a horizontally disposed bearing face extending beyond the rail and an angularly disposed swinging clamping member having the outer end anchored to the bearing face and the other end provided with spaced jaws gripping the adjacent side of the rail base.
10. In a rail anchor, the combination with the base of a rail and a tie supporting the rail, of a member adapted to extend under the rail and having one end spaced from the tie and provided with means for engaging said rail base and the other end engaging the tie and provided with a horizontally disposed bearing face extending beyond the rail, an upstanding curved shoulder formed on the bearing face in a position remote from the rail and adjoining the tie, a flange overhanging the shoulder and an angularly disposed swinging clamping member resting on the bearing face and having the outer end engaging the shoulder and the inner end formed to present gripping jaws receiving the adjacent edge of the rail base.
15. In a rail anchor, the combination with the base of a rail and a tie supporting the rail, of a member adapted to extend under the rail and having one end spaced from the tie and provided with means for engaging said rail base and the other end engaging the tie and provided with a horizontally disposed bearing face extending beyond the rail and an angularly disposed swinging clamping member having the outer end anchored to the bearing face and the other end provided with spaced jaws gripping the adjacent side of the rail base.
20. In a rail anchor, the combination with the base of a rail and a tie supporting the rail, of a member adapted to extend under the rail and having one end spaced from the tie and provided with means for engaging said rail base and the other end engaging the tie and provided with a horizontally disposed bearing face extending beyond the rail, an upstanding curved shoulder formed on the bearing face in a position remote from the rail and adjoining the tie, a flange overhanging the shoulder and an angularly disposed swinging clamping member resting on the bearing face and having the outer end engaging the shoulder and the inner end formed to present gripping jaws receiving the adjacent edge of the rail base.
25. In a rail anchor, the combination with the base of a rail and a tie supporting the rail, of a member adapted to extend under the rail and having one end spaced from the tie and provided with means for engaging said rail base and the other end engaging the tie and provided with a horizontally disposed bearing face extending beyond the rail, an upstanding curved shoulder formed on the bearing face in a position remote from the rail and adjoining the tie, a flange overhanging the shoulder and an angularly disposed swinging clamping member resting on the bearing face and having the outer end engaging the shoulder and the inner end formed to present gripping jaws receiving the adjacent edge of the rail base.
30. In a rail anchor, the combination with the base of a rail and a tie supporting the rail, of a member adapted to extend under the rail and having one end spaced from the tie and provided with means for engaging said rail base and the other end engaging the tie and provided with a horizontally disposed bearing face extending beyond the rail, an upstanding curved shoulder formed on the bearing face in a position remote from the rail and adjoining the tie, a flange overhanging the shoulder and an angularly disposed swinging clamping member resting on the bearing face and having the outer end engaging the shoulder and the inner end formed to present gripping jaws receiving the adjacent edge of the rail base.
35. In a rail anchor, the combination with the base of a rail and a tie supporting the rail, of a member adapted to extend under the rail and having one end spaced from the tie and provided with means for engaging said rail base and the other end engaging the tie and provided with a horizontally disposed bearing face extending beyond the rail, an upstanding curved shoulder formed on the bearing face in a position remote from the rail and adjoining the tie, a flange overhanging the shoulder and an angularly disposed swinging clamping member resting on the bearing face and having the outer end engaging the shoulder and the inner end formed to present gripping jaws receiving the adjacent edge of the rail base.
6. A rail anchor comprising an abutment arranged to engage one side of a rail base, a fulcrumed rail gripping member at the opposite side of the rail base provided with upper and lower gripping jaws engaging corresponding surfaces of the said base, said jaws defining between them a wedge-shaped gripping space receiving the rail base therein and being normally inclined with respect to said base.
7. A rail anchor comprising a body member adapted to extend transversely beneath a rail base and provided at one end with an abutment adapted to engage one side of the said base, said body portion being provided at its opposite end with a bearing surface disposed below and projecting beyond the opposite side of the base and terminating in a vertical wall portion, a rail gripping member having one end in fulcrum engagement with said vertical wall portion and the opposite end provided with upper and lower gripping jaws receiving the adjacent edge of the rail base therebetween.
10. A rail anchor comprising a body member adapted to extend transversely beneath a rail base and provided at one end with an abutment adapted to engage one side of the said base, said body portion being provided at its opposite end with a bearing surface disposed below and projecting beyond the opposite side of the base and terminating in a vertical wall portion, a rail gripping member having one end in fulcrum engagement with said vertical wall portion and the opposite end provided with upper and lower gripping jaws receiving the adjacent edge of the rail base therebetween.
15. A rail anchor comprising a body member adapted to extend transversely beneath a rail base and provided at one end with an abutment adapted to engage one side of the said base, said body portion being provided at its opposite end with a bearing surface disposed below and projecting beyond the opposite side of the base and terminating in a vertical wall portion, a rail gripping member having one end in fulcrum engagement with said vertical wall portion and the opposite end provided with upper and lower gripping jaws receiving the adjacent edge of the rail base therebetween.
20. A rail anchor comprising a body member adapted to extend transversely beneath a rail base and provided at one end with an abutment adapted to engage one side of the said base, said body portion being provided at its opposite end with a bearing surface disposed below and projecting beyond the opposite side of the base and terminating in a vertical wall portion, a rail gripping member having one end in fulcrum engagement with said vertical wall portion and the opposite end provided with upper and lower gripping jaws receiving the adjacent edge of the rail base therebetween.
25. A rail anchor comprising a body member adapted to extend transversely beneath a rail base and provided at one end with an abutment adapted to engage one side of the said base, said body portion being provided at its opposite end with a bearing surface disposed below and projecting beyond the opposite side of the base and terminating in a vertical wall portion, a rail gripping member having one end in fulcrum engagement with said vertical wall portion and the opposite end provided with upper and lower gripping jaws receiving the adjacent edge of the rail base therebetween.
30. A rail anchor comprising a body member adapted to extend transversely beneath a rail base and provided at one end with an abutment adapted to engage one side of the said base, said body portion being provided at its opposite end with a bearing surface disposed below and projecting beyond the opposite side of the base and terminating in a vertical wall portion, a rail gripping member having one end in fulcrum engagement with said vertical wall portion and the opposite end provided with upper and lower gripping jaws receiving the adjacent edge of the rail base therebetween.
35. A rail anchor comprising a body member adapted to extend transversely beneath a rail base and provided at one end with an abutment adapted to engage one side of the said base, said body portion being provided at its opposite end with a bearing surface disposed below and projecting beyond the opposite side of the base and terminating in a vertical wall portion, a rail gripping member having one end in fulcrum engagement with said vertical wall portion and the opposite end provided with upper and lower gripping jaws receiving the adjacent edge of the rail base therebetween.

Signed at Winnipeg; this 10th day of February, 1921.

WILLIAM ANDREW ROBERT ANGUS.

In the presence of—

GERALD S. ROXBURGH,
K. B. WAKEFIELD.
